MOLD FOR USE IN THE MANUFACTURE OF
DRY RECTIFIERS

Alexander Jenkins, King's Cross, London, England, assignor to Westinghouse Brake and Signal Company Limited, London, England

Application July 16, 1951, Serial No. 236,972

Claims priority, application Great Britain

2 Claims. (Cl. 49—65)

1

This invention relates to the manufacture of dry rectifiers of the kind comprising a body of semi-conducting material carried by a metal support or holder and is particularly applicable to the manufacture of small rectifier elements of this kind of such a size, for example, as are used in alternating current measuring instruments.

Such small rectifier elements are troublesome to handle, this disadvantage being particularly apparent in the manufacture of so-called crystal rectifiers, such as germanium or silicon rectifiers, when securing the semi-conductor to the metal support or holder.

The manufacture of these crystal rectifiers usually involves the step of cutting wafers of the desired size from a larger rod or ingot of the semi-conductor material, which is an operation of some intricacy due to the small size of the wafers.

It is the object of the invention to provide a mould for the manufacture of dry rectifiers whereby the moulded semi-conductor is more easily applied and secured to the metal support or holder and which also, in the case of crystal rectifiers, eliminates the necessity of cutting wafers from rods or ingots of the semi-conductor material.

According to the invention, a mould for the manufacture of dry rectifiers of the above kind includes means for casting a body of semi-conductor material in the form of a number of projections each of a suitable size and shape to fit its metal support or holder and connected by a thin web.

The body is divided up into individual elements by cutting or fracturing the web between the projections, preferably after securing to the supports or holders.

Certain semi-conductor materials, for example, germanium, when in the molten state, have a high surface tension which makes it impossible to cast elements of the small size contemplated by the present invention by the normal method of straight forward pouring of the molten material into a suitable mould and this difficulty is overcome according to the invention by subjecting the semi-conductor material and the mould to a vacuum, melting the semi-conductor material, and then forcing the molten material into the mould by destroying the vacuum.

The invention will now be described with reference to the accompanying drawing which illustrates one form of mould suitable for carrying out one of the steps of the process, of which

Figure 1 is an end view;

2

Figure 2 is a cross-sectional view taken along the line II—II of Figure 1;

Figure 3 is a view of the other end of the mould;

Figure 4 is a cross-sectional view taken along the line IV—IV of Figure 2;

Figure 5 is a perspective view of the two parts of the mould with the centre plug removed; and

Figure 6 illustrates the cast body when removed from the mould.

According to one method of carrying out the invention, the body of semi-conductor material is cast in a mould, comprising a block 1 of carbon or other suitable material such as silica, provided with a tapered bore 2 of circular cross section into which fits a similarly tapered plug 3 of such a length that, when it is fully inserted into the bore, it does not extend the full length of the bore so that the end of the plug forms the base of a receptacle or crucible 4 of which the portion of the bore extending beyond the end of the plug forms the sides. Radially spaced around the circumference of the plug are provided two longitudinally extending "flats" 5 which, when the plug is inserted into the bore, form shallow chambers 6 into which the molten material flows from the crucible as described hereinafter. Radially along the length of each of the "flats" recesses 7 are formed. These recesses are conical or of such other shape and size as corresponds with the shape and size of the metal holders which are to receive the semi-conductor in the finished rectifier element. The end of the plug forming the base of the crucible is provided with a conical recess 8, co-axial with the plug, communicating at its apex through a bore 9 and passages 10 with the chambers 6.

The tapered plug 3 is inserted into the bore and the mould is supported so that the two are substantially vertical with the crucible 4 formed at the end of the bore uppermost. A quantity of the semi-conductor material is inserted in the crucible and the atmosphere evacuated to a few millimetres of mercury. The mould is then heated, by high frequency induction for example, until the semi-conductor is molten, whereupon the vacuum is suddenly destroyed. This results in the forcing of the molten material from the crucible 4 through the passage 10 into the chambers 6 and recesses 7. When using some semiconductor materials it is necessary to take precautions against oxidation or other chemical changes and/or to prevent the absorption, whilst in its molten state, of certain impurities. In such cases the vacuum should be destroyed by the

introduction of a suitable gas. For example, when germanium is the semi-conductor an inert gas such as argon, hydrogen or nitrogen may be used. On the other hand, the characteristics of some semi-conductors are improved by the addition of certain impurities and this may be accomplished by the use of a suitable gas to destroy the vacuum. Similarly, although in the example described herein the mould is stated to be of carbon or silica, it will be understood by those skilled in the art that the choice of material will be governed by a consideration of the effect that certain materials have upon the semi-conductor material being used.

After cooling, which may be controlled, if desired, to produce a favourable crystalline structure of the material, the plug is loosened by tapping the projecting end 11 and is withdrawn from the block and the semi-conductor is removed in the form of a number of projections 12, each of a suitable size and shape to fit their metal holders, connected by a thin web 13, somewhat in the form of a comb (see Fig. 6).

The semi-conductor is then supported in a jig which may be in the form of a perforated sheet 25 while a metal coating is deposited, in any suitable manner, upon the sides of the projections which are then soldered into their metal holders and the individual elements separated by breaking the connecting web.

The above-mentioned mould has the advantages that it is easily split in order to release the castings, that it needs no special alignment when re-assembling and also that it ensures a constant size of casting without the necessity of measuring 30 accurate quantities of the material.

Having thus described my invention, what I claim is:

1. For use in a process for the manufacture of dry rectifiers, a mould comprising, in combination, a block having a tapered bore extending therethrough; a plug correspondingly tapered for fitting said bore and having recesses formed in a cutaway portion of the tapered surface thereof; and a crucible formed by one end of said plug and the wall of said bore extending beyond said end, a passage extending between said crucible and said cutaway portion.

2. For use in a process for the manufacture of dry rectifiers, a mould comprising, in combination, a block having a tapered circular bore extending therethrough; a cylindrical plug correspondingly tapered for fitting into said bore and having at least one longitudinally extending flat formed on the tapered surface thereof with a number of radial recesses formed therein; and a crucible formed by one end of said plug and the wall of said bore extending beyond said end, a passage extending between said crucible and a chamber formed between said flat and the bore.

ALEXANDER JENKINS.
